CRANKCASE VALVE FOR TWO-CYCLE ENGINE
Elmer C. Kiekhaefer, Cedarburg, Wis.
Application December 28, 1950, Serial No. 203,138
6 Claims. (Cl. 123—73)

This invention relates to crankcase induction valve means for two-cycle, internal-combustion engines, and particularly two-cylinder, alternate-firing engines.

The invention provides a crankcase induction reed valve unit which admits and directs the fuel mixture into the crankcase in converging streams directed radially towards and arranged about the center-main crankshaft bearing in each crank chamber.

A principal object of the invention is to provide a reed valve unit which will operate more efficiently to admit greater fuel charges into the crank chamber.

A more particular object is to predetermine the flexing action of the reeds of the valve unit and eliminate backing plates to limit the opening movement of the reeds.

Another object is to provide an efficient arrangement of the reeds with respect to the limited dimensions of the crank chamber of an engine.

These and other objects and advantages will be more fully set forth in the following description of a preferred embodiment of the invention as illustrated in the accompanying drawings.

In the drawings:

Figure 1 is a cross-sectional view of a two-cycle, alternate-firing, two cylinder engine employing crankcase pre-compression with one piston removed to show the intake ports and with the reed valve center bearing block shown in Figs. 2 to 5;

Fig. 2 is a perspective enlarged view of the split bearing block adapted to support the center-main bearing of an engine crankshaft and showing the passages as formed therein for the crankcase induction system of the engine;

Fig. 3 is an enlarged plan view of the joined block showing the reed sections therefor as arranged on one face of the block, and with one reed broken away and sectioned;

Fig. 4 is a view taken on line 4—4 of Fig. 1 through the members of the bearing block; and

Fig. 5 is a section of one of the reeds taken on line 5—5 of Fig. 3.

The engine shown in the drawings comprises the cylinder block 1 and crankcase member 2 which join in a transverse plane passing through the axis of the engine crankshaft 3. Crankshaft 3 is supported at each end in the bearing assemblies 4 which serve to close the opposite ends of the crankcase 5 formed jointly by cylinder block 1 and member 2.

Each of the two cylinder bores 6 opening into crankcase 5 carries a piston 7 connected by a rod 8 to the corresponding upper and lower crank throws 9 and 10, respectively, of crankshaft 3. Crank throws 9 and 10 are spaced 180° with respect to the crankshaft axis so that the pistons reciprocate in opposite directions for alternate firing or with each 180° of crankshaft rotation.

Crankcase 5 is divided into the separate upper and lower crank chambers 11 and 12 by the bearing block 13.

In the operation of the engine, the fuel mixture is admitted into each cylinder through the corresponding passage 14 in the side of cylinder block 1. Each passage 14 communicates with the respective crank chamber and opens through ports 15 into the respective cylinder bore 6. The exhaust gases are discharged through opposite ports as indicated at 16 and opening from each cylinder bore into suitable exhaust means, not shown. The intake and exhaust ports of each bore are controlled by the respective piston which opens the ports at the lower end of each piston stroke and otherwise closes the ports 80 during the compression and power stroke.

2

The precompression of the fuel mixture for transfer through passages 14 to the respective cylinder and to displace the exhaust gases remaining in the fired cylinder is effected within each crank chamber by the corresponding piston during the downward power stroke. The two complementary, semi-circular bearing members 17 comprising block 13 are joined by bolts 18 passing therethrough on each side of a central axial bore 19. Bore 19 is adapted to fit and receive the center journal 20 of crankshaft 3 between crank throws 9 and 10 for the journal support of the crankshaft. The outer dimension of members 17 fit the corresponding machined inner surface of crankcase 5 to divide the latter as referred to above.

15 The induction manifold passages 21 in each member 17 jointly register with the opening 22 in crankcase member 2. The carburetor 23 secured to and carried by crankcase member 2 provides for delivery of the fuel mixture through opening 22 to passages 21 from which the fuel 20 is selectively admitted to chambers 11 and 12 through the ports 24.

25 Ports 24 are arranged in block 13 around bore 19 and open from the upper and lower faces of the block. The ports are spaced in a circle and spaced from the outer dimension of the block. The series of holes 25 are drilled and tapped in the marginal body of the block providing at least one hole 25 adjacent to a port.

26 The reeds 26 normally seated on the upper and lower faces of the block to cover ports 24, control the admission 30 of fuel mixture to the respective chambers. During the up-stroke of the piston a reduced pressure is obtained within the chamber which allows the fuel mixture at atmospheric pressure within passages 21 to lift the reeds from the block to open the port.

35 Each reed 26 comprises a flexible, thin, spring-steel piece which is secured flatwise at one end thereof on the face of block 13 by a bolt 27 secured in a corresponding hole 25, and extends lengthwise over the corresponding port normally to close the same as described.

40 For maximum service, the flexing of the reeds must be restricted to within the elastic limits of the metal and the stresses should be distributed evenly throughout the length of the reed.

45 In the operation of the engine the reeds controlling ports 24 to chambers 11 and 12 respectively, operate in unison. The pressure effectively lifting the reeds to open the ports decreases toward the free end of the reeds as the gas enters the chamber. Straight, rectangular reeds tend to be over-flexed toward the base or secured end and accordingly require supporting means on the back side to limit the flexing uniformly along the length of the reed.

50 According to the present invention, the lateral dimension of each reed 26 varies from its unsecured end to the secured end whereby a certain natural flexibility is obtained and which corresponds with the desired deflection for even distribution of the stress.

Generally, the reed should taper from a wider secured end to a narrower free end so that the flexibility of the reed generally increases toward the free end and a greater angular deflection of the reed is obtained toward the free end. The dimensions of the reed must be determined with relation to the size and location of the port and the shape of the port or with respect to the effect of the gas mixture passing through the port and striking the underside of the reed. Generally, however, the port may be dimensioned to correspond with the respective reed and to provide sufficient seating area around the port for a tight closure.

55 The tapered reed providing the desired flexibility is particularly adapted to be arranged circularly about an axis and in a reed valve unit on the circular valve block 13 shown and described.

60 The secured ends of the reeds 26 extend to the circumferential edge of block 13 and similarly abut the machined inner face of crankcase 5 so as to be relatively located on bolts 27 without the use of pins, or the like.

65 Various embodiments of the invention may be employed within the scope of the following claims.

1. In an internal-combustion engine, a crankshaft

having a main journal, a crankcase for said crankshaft, a circular journal bearing member assembled on said journal and forming one end wall of said crankcase, a fuel supply passage in said bearing member opening through a series of ports formed therein, said ports being spaced circumferentially about said journal, and a series of flexible reeds secured to said bearing member adjacent the periphery thereof and normally extending radially of said journal and seated on said member to close the respective ports, each of said reeds being of substantially uniform thickness and tapering in width from the wider secured end to the narrower free end whereby each reed is subject to more uniform flexure through its free length.

2. In a crankcase valve for two-cycle engines and the like comprising a circular valve block forming one end of the engine crankcase and having an induction passage, and a series of ports opening from the face of said block, a series of flexible reeds secured at their outer ends against the face of said block and extending radially inwardly and normally seated over said ports to close the latter, said reeds being of a generally uniform thickness and of a width diminishing from the secured ends thereof whereby the movement of the reeds by the gas acting thereagainst to open said ports is substantially limited to a uniform angular deflection and the reed is accordingly more uniformly stressed throughout its free length.

3. In an internal-combustion engine, a crankshaft having a main journal, a crankcase for said crankshaft having a circular inner wall, a circular journal bearing member assembled on said journal and forming one end wall of said crankcase, a fuel supply passage in said bearing member opening through a series of ports formed therein, said ports being spaced circumferentially about said journal, and a series of flexible reeds secured to said bearing member adjacent the periphery thereof and normally extending radially of said journal and seated on said member to close the respective ports, each of said reeds being of substantially uniform thickness and tapering in width from the outer wider secured end to the inner narrower free end whereby each reed is subject to more uniform flexure through its free length and abutting at the outer end thereof the inner wall of said crankcase so as to be located with respect thereto.

4. In an internal-combustion engine, a crankshaft having a crank, a crank chamber therefor having an end wall axially spaced from said crank and including bearing means journaly supporting said crankshaft, a series of ports in said wall arranged about said bearing means for the admission of a fuel mixture to said chamber during the induction cycle of said engine, and a series of reeds secured to said wall and disposed to control the admission of fuel mixture through said ports and when open to direct the fuel mixture radially inwardly toward said crank whereby the fuel mixture is given a rotational velocity upon entering said chamber tending to increase the induction cycle of said engine.

5. In an internal-combustion engine, a crankshaft, a crank case for said crankshaft, a bearing member including bearing means journaly supporting said crankshaft between crank-throws and dividing said crank case into individual crank chambers adapted to receive a fuel mixture for precompression, said member having a passage and a series of ports arranged about said bearing means for the admission of the fuel mixture to said chambers during the induction cycle of the respective chamber, and a series of reeds secured to said member and disposed to control the admission of fuel mixture through said ports and when open to direct the fuel mixture radially inwardly toward the respective crank-throw whereby the fuel mixture is given a rotational velocity upon entering the chamber tending to increase the induction cycle of said engine.

6. In an internal-combustion engine, a crankshaft, a crank case for said crankshaft, a bearing member including bearing means journaly supporting said crankshaft between crank-throws and dividing said crankcase into individual crank chambers adapted to receive a fuel mixture for precompression, said member having a passage and a series of ports arranged about said bearing means for the admission of the fuel mixture to said chambers during the induction cycle of the respective chamber, and a series of reeds secured to said member and disposed to control the admission of fuel mixture through said ports and when open to direct the fuel mixture radially inwardly toward the respective crank-throw whereby the fuel mixture is given a rotational velocity upon entering the chamber tending to increase induction cycle of said engine, said reeds being of a generally uniform thickness and of a width diminishing from the secured ends thereof whereby the movement of the reeds by the gas acting thereagainst to open said ports is substantially limited to a uniform angular deflection and the reed is accordingly more uniformly stressed throughout its free length.
